DESIGN FOR A COMBINED GRAVE MARKER AND FLOWER HOLDER

Stanley A. Waligorski, Reading, Pa.

Application August 16, 1939, Serial No. 86,731

Term of patent 14 years

To all whom it may concern:

Be it known that I, Stanley A. Waligorski, a citizen of the United States residing at Reading, in the county of Berks and State of Pennsylvania, have invented a new, original, and ornamental Design for a Combined Grave Marker and Flower Holder, of which the following is a specification, reference being had to the accompanying drawing, forming part thereof.

Fig. 1 is a front elevational view of a combined grave marker and flower holder embodying my design, the words and numerals shown thereon being illustrative only.

Fig. 2 is a plan view of the same.

Fig. 3 is a vertical sectional view taken on the line 3—3 of Fig. 1.

I claim:

The ornamental design for a combined grave marker and flower holder, as shown and described.

STANLEY A. WALIGORSKI.
